US0D1110314S

(12) **United States Design Patent** (10) Patent No.: **US D1,110,314 S**
(45) Date of Patent: ** Jan. 27, 2026

(54) **HARD DRIVE ENCLOSURE**

(71) Applicant: **Ji'an Zhongrui Electronics Co., Ltd.**,
Jiangxi Province (CN)

(72) Inventors: **Xiaodong Ma**, Ji'an County (CN);
Xude Zhou, Ji'an County (CN);
Xianzhang Wu, Ji'an County (CN)

(**) Term: **15 Years**

(21) Appl. No.: **35/522,688**

(22) Filed: **Aug. 29, 2024**

(80) **Hague Agreement Data**

Int. Filing Date: **Aug. 29, 2024**

Int. Reg. No.: **DM/241031**

Int. Reg. Date: **Aug. 29, 2024**

Int. Reg. Pub. Date: **Oct. 18, 2024**

(51) **LOC (15) Cl. 14-02**

(52) **U.S. Cl.**

USPC **D14/348**

Assistant Examiner — Alison Davis

(57) **CLAIM**

The ornamental design for a hard drive enclosure as shown and described.

DESCRIPTION

1. Hard drive enclosure

1.1: Perspective

1.2: Front

1.3: Back

1.4: Left

1.5: Right

1.6: Top

1.7: Bottom

1.8: Perspective

The parts shown by means of broken lines in the reproductions are not part of the claimed design.

1 Claim, 8 Drawing Sheets
